UNITED STATES PATENT OFFICE.

THOMAS HARVEY McDONALD, OF TROPICO, AND STEPHEN W. MACK, OF GLENDALE, CALIFORNIA, ASSIGNORS TO McDONALD OIL AND WATER ELEVATOR CO., OF ABERDEEN, WASHINGTON, A CORPORATION OF WASHINGTON.

OIL AND WATER ELEVATOR.

1,113,028.

Specification of Letters Patent.

Patented Oct. 6, 1914.

Application filed November 24, 1911. Serial No. 662,330.

To all whom it may concern:

Be it known that we, THOMAS HARVEY McDONALD and STEPHEN W. MACK, citizens of the United States, said McDONALD, residing at Tropico, in the county of Los Angeles and State of California, and said MACK residing at Glendale, in said county and State, have invented new and useful Improvements in Oil and Water Elevators, of which the following is a specification.

This invention relates to that class of oil and water elevators illustrated in the patent of the United States No. 970,098, patented Sept. 13, 1910, to said Thomas Harvey McDonald.

The object of this invention is to perfect the novel oil and water elevator shown in the said patent in the following respects:—First,—the footway is closed at the foot wheel, and the inlet to the foot way is located in the ascending tubing of the pump at a distance above the foot wheel, thus to minimize the wear upon the foot wheel by preventing sand from coming into contact therewith. Second,—the foot of the pump is provided with a protector or digger to protect the foot wheel from damage resulting from striking the bottom of the well and also to loosen the sand at the bottom of the well. Third,—improved means are connected with the foot to lower and raise the foot. Fourth,—a novel and improved construction of the pump stock is provided, including the descending and ascending tubes or pipes and means for holding the same together and in position. Fifth,—means are provided for lowering the foot wheel and for operating the elevator at different depths without changing the operative relation of the parts and without splicing the cable. Sixth,—the mechanism for placing and handling the pump stock in the process of installing and operating the same is improved. Seventh,—means are provided to improve the operation of the pumping cable. Eighth,—improved means are provided to drive the pumping cable.

An object of the invention is to provide an endless line oil and water elevator for wells of great depth. A difficulty to be overcome in apparatus of this kind is the liability of the bucket-carrying line to slip on the driving drums because of the great resistance resulting from friction and from

the inertia of the liquid as it is being started from rest and also the friction thereof as it moves upward through the tubing.

An object of the invention is to prevent such slipping.

Other objects and advantages may appear from the subjoined detail description.

The accompanying drawings illustrate the invention.

Figure 1 is a broken elevation of apparatus embodying this invention showing the pump installed in operating position and capable of being lowered about three-fourths the depth of the derrick as the sand is pumped out of the well. A broken section of the earth formation is shown. Fig. 2 is a fragmentary detail illustrating the method of threading the pumping line. Some of the parts are in section and are viewed from the left of Fig. 1. Fig. 3 is an enlarged plan section of the pump stock on line x^3 , Fig. 1, showing the slotted temporary tubing in place. Fig. 4 is a fragmentary detail illustrating on a smaller scale than Fig. 3 features of construction of the pump stock with temporary tubing, there being shown fragments of the pumping line and core, a split coupling and a detached fragment of a split tubing to fit in said coupling. Fig. 5 is a fragmentary view on a smaller scale than Fig. 4 of portions of the pump stock and pumping line in position above the surface of the ground ready to be lowered and a fragment of the casing in the ground. Fig. 6 is a plan section on the scale of Fig. 10 from line x^6 , Figs. 8, 9, 10. Fig. 7 is a section on the scale of Fig. 10, looking up from line x^7 , Figs. 8, 9, 10. Fig. 8 is an elevation partly in section of the lower end of the pump in place in a well-casing, and viewed from the same side as Fig. 1. Fig. 9 is a fragmental elevation partly in section from line x^9 — x^{10} , Fig. 8, viewed from the right in Fig. 1. Fig. 10 is an enlarged fragmental detail of parts shown in the lower part of Fig. 9; and in section on line x^9 — x^{10} , Fig. 8, looking in the direction of the arrows. Fig. 11 is a plan section on the scale of Fig. 10 from line x^{11} , Figs. 10 and 12. Fig. 12 is a fragmentary view of the pump stock at a joint. Fig. 13 is a fragmentary view of a section of the pump stock ready to be put onto an installed pump tubing for the purpose of low-

ering the foot. Fig. 14 is a fragmentary view of a portion of the pump stock ready to receive the section shown in Fig. 13. Fig. 15 is an elevation of the rope driving mechanism at the top of the pump. Fig. 16 is an elevation of said mechanism from the right of Fig. 15. The fluid carrier is sectioned on line x^{16} , Fig. 15. Fig. 17 is a fragmentary sectional elevation from line x^{17} , Fig. 15, looking toward the left. Fig. 18 is a fragmental sectional detail of the guide for the tightening pulley. Fig. 19 is a fragmental plan section on line x^{19} , Fig. 9.

Arrows on the section lines indicate the direction of sight.

The foot 1 is made in halves a , b , fastened together by bolts 2 and provided in their inner faces with recesses 3 and together form a chamber for the foot wheel and also a foot way or bucket way for the pumping line and buckets.

The inlet or intake 4 of the pump is located in a limb 5 of the ascending pump tubing at a considerable height above the level of the foot wheel 6 that is mounted in the recesses 3 on chamfered stub axles 7 carrying bearing balls 8 that run in a race way c provided in the mid-plane of the wheel, surrounding the abutting chamfered ends 30 of the axles.

The descending tubing is formed of sections 9 connected by couplings 10. Like couplings 10 serve to connect the sections of the ascending pump tubing. The top of the foot piece is provided around the entrance and exit to and from the foot chamber with sockets 11, 11' to seat the lower ends of the descending and ascending pump tubing. The lower end of each section of tubing is 40 reamed as indicated at 12 in Fig. 10, to avoid liability of engaging the buckets 13 of the endless pumping line 14 which is preferably a steel wire cable. The buckets 13 are located at intervals along the pumping line between front and rear stops 15, 16, which are spaced apart a distance greater than the length of a bucket to allow the buckets to move a short distance along the line to prevent binding at the lower end of the line as the buckets go around the foot wheel.

The distance between the buckets is preferably somewhat less than the distance between the foot wheel and the inlet 4 of the ascending pump tubing, so that when the pump is in operation, oil or water entering the inlet 4 and flowing toward the chamber at 3 in the foot will be caught by the ascending bucket before the oil or water reaches said chamber, thus keeping any sand which may be carried by the oil or water from reaching the foot wheel. The ball-bearings 8 for the foot wheel axle are inclosed by the foot piece, so that no sand can get to said ball-bearings from the outside. The ball-bearings 8 are arranged inside the foot

wheel at the mid-plane thereof so as to minimize the friction.

The bucket-way at 3 in the foot is of uniform diameter at its inlet and outlet, with the bore of the descending pump tubing 9. 70 The bore of the ascending pump tubing 5 is of smaller diameter than the bucket-way and is connected therewith by a taper nipple e , the bore of which tapers from the diameter of the foot-way to that of the ascending pump tubing 5 which is of less diameter than the descending pump tubing and of the foot-way in order that the buckets may fit the ascending pump tubing to carry up the liquid; and will be free from the walls 80 of the descending pump tubing and of the foot-way so as to avoid friction and minimize the resistance of confined air.

The pump tubing is supported by a line 17 connected at intervals with a sectional 85 core. The lower section 18 of said core is preferably metal and is secured to the supporting line 17 by Babbitt metal 19 molded in a socket 20 in the core section 18 around the spread-out strands 21 of the line. Said core is provided in opposite sides with grooves 22 to fit the pump tubing; and the sections thereof above the foot section 18 are preferably of wood and form clamp supports at intervals from the section 18 to 95 the top of the well-casing 23.

The joints between the tubing sections and the core sections are staggered, so that when the sections are fastened together by clamps 24 they will form a rigid pump stock from 100 the foot-piece to the top of the well.

The digger foot-piece may be made of two channel irons 25 fastened together by bolts 26, 27, 28, 29 and thereby securely fixed to the foot-piece and the core; the bolts 26 105 fastening the lower ends of the channel irons together; the bolt 28 fastening the channel iron to the lower section 18, and the bolts 29 fastening the channel irons to a wooden section 18' of the core.

The derrick 30 is provided with the supporting pulley 31 and bull-wheel 32, on the spool 33 of which bull-wheel is wound a sufficient length of supporting line 17 to extend to the top of the derrick 30 and over the supporting pulley 31 and thence down to the bottom of the well, so that when said supporting line is fastened to the bottom core section 18, thereby operating the bull-wheel with the usual well rig machinery, not shown, the pump stock, when assembled and attached may be lowered and raised as required.

In order to install the apparatus at a well provided with a derrick, a sufficient length 125 of wire cable supporting line 17 will first be wound on the spool of the bull-wheel and then led over the supporting pulley 31 and down to the ground where it will be inserted downwardly through the bottom section 18 130

of the core and its strands spread apart and then drawn back into the socket 20 which will be filled with Babbitt metal 19.

The nipple *e*'' of the ascending tubing 5 and the lower section 9 of the descending tubing will be inserted respectively into the sockets 11, 11' and a slip coupling 10 will be slipped over the upper end of the nipple. Then the metal core section 18 will be slid 10 into place between the descending tubing section 9 and the coupling 10; said core section 18 being provided with an enlargement *d* of one of the grooves 22 to accommodate the slip coupling 10.

15 When the core section 18 abuts against the foot 1, the intake section 5 of the assembled tubing will be slipped along the groove 22 into the coupling 10 and then the wooden core section 18' will be slid into place between the descending and ascending tubings. Then the channel iron sections 25 are applied to the sides of the foot and core and are fastened in place by the bolts 26, 27, 28, 29, the bolt 28 being made to pass through 25 the socket 20 and through the Babbitt metal and cable strands therein. A clamp 24 will then be applied and a hook bolt *f* will then be applied to hold the cable 17 centrally of the core and then the bull-wheel will be operated 30 to lift the portion of the pump thus completed into upright position and it is then brought over the well casing and lowered thereinto until new sections of the pump stock may be applied.

35 It is desirable that the foot wheel shall be of as great diameter as practicable so as to avoid too short a bend of the cable at the bottom of the pump and it is also desirable that the pump stock shall be of as small 40 cross-sectional area as possible so as to minimize cost and weight. Therefore the bottom core section and the core section next above, are tapered diminishing upwardly to the cross-sectional area deemed practical for 45 the main body of the pump stock core.

The pump stock sections are made by clamping descending and ascending pump tubings 5'' and 9'' in place on opposite sides of the grooved wooden core sections 18'. 50 The core section and tubing sections are of equal length but the core section of each pump stock section is in staggered relation to the tubing sections which are even with each other. The upper end of the core section 55 projects above the level of the upper end of the tubing sections and its lower end terminates above the lower ends of such tubing sections. Slip couplings 10 are provided to hold the abutting ends of the tubing sections together.

60 Before applying one pump stock section to the top of another, the clamps 24 must be loosened and the section to be applied will be loosened to allow the tubing to spread 65 apart sufficiently to slide along the core 18'

until seated in the slip couplings 10, then the clamps 24 will be tightened and an additional clamp applied to the lower ends of the tubing just inserted so that the tubing is clamped to the core sections immediately 70 above and below the joint between the same as indicated at Fig. 12.

The core sections 18' are provided with hook bolts *f* clamping the supporting line to the respective sections. At each bolt a 75 clamp plate *g* is provided and by tightening the bolt the supporting line is clamped tightly against the clamp plate so that each section is independently supported by the supporting line. In this manner the weight 80 is distributed and liability of jamming or separating the ends of the tubing sections is avoided.

The work of adding to and lowering the pump stock will be continued section by section until the depth at which the work of pumping is to be begun has been reached by the foot. Then a sufficient length of pumping line 14 with buckets 13 and front and rear stops 15, 16, thereon will be provided 90 and a threading line *m* provided with a flexible coiled spring sheath *h* and having at its end a socket *i* adapted to be grappled by the spring arms of the spear head *j*, is inserted down the descending tubing 9'' and 9 until the socket *i* has passed the foot wheel. Thereupon the fishing line *k* will be lowered through the ascending tubing 5 and will grapple the socket *i*. The threading line *m* then being fastened to one end of the pumping line 14 will be drawn by the fishing line *k* down around the foot wheel 6 and in this manner the pumping line will be threaded through the pump.

The pumping line 14 is bent over a take-up pulley 34 directly above the ascending limb of the pump tubing and when threaded as above described, passes thence down around the foot wheel 6 and up through and out at the top of the top ascending limb section 5''' which terminates above the spout 35. Thence the line is wound a plurality of times around two grooved drums 36, 37, passing first over the drum 36 and thence directly around the drum 37 and so on 115 around 36 and 37 the required number of times and then is returned upward from the bottom of the drum 36 and thereupon the ends of the line are spliced together, thus completing the endless chain by which the 120 pumping is to be done. The pulley 34 is vertically movable by means of a connection 38 led over pulleys 39, 40 at the top of the derrick and thence down to a sand reel 41 by which this connection can be handled. 125 The pulley 34 will then be drawn up to tighten the pumping line.

Motion is transmitted to the drums 36, 37, from a driving shaft 42 which is provided with sprocket wheels 43, 44, to drive 130

sprocket chains 45, 46, that in turn drive the drum sprocket wheels 47, 48, mounted on the said drums which are carried by the shafts 49, 50, that are mounted on slanting beams 51 which are supported by the posts 52. By driving the pumping line from two positively driven drums 36, 37, liability that the line will slip is minimized.

- 10 In order to avoid creepage of the pumping line on the two drums 36, 37, under various loads the driving sprocket wheels 43, 44 are provided with reversely-arranged ratchet clutches 53, 54 respectively having hubs 55 fixed by suitable means indicated by set-screws 56 to the driving-shaft 42 upon which the driving-sprocket-wheels 43, 44 are journaled to allow relative rotation between the shaft 42 and said sprocket wheels.
- 15 20 When the load upon the pumping line is heavy there appears to be no tendency of said line to creep; but when the load lightens, the pumping line and the sprocket chain do not run in unison, thus causing a tightening of the normally loose lower limb of the upper sprocket chain 45 or the normally loose upper limb of the lower sprocket chain 46.

It is desirable that the chains 45 and 46 operate simultaneously at all times to drive their respective drum wheels 47 and 48; and this is approximated by the provision of the reversely-arranged ratchet clutches shown which prevent those limbs of the sprocket chains which should be loose from becoming tight.

The drums 36, 37 are of like construction and each comprises a hub 57, see Fig. 17, mounted on a shaft 49 or 50, as the case 40 may be, and provided with a web 58 provided with an intermediate collar 59 and with an arm 60 and flange forming a seat to receive a portion of the tread 62, which is preferably made of wooden segments arranged with the grain extending radially. An annular clamp ring 63 comprising the web 64, shoulder 65 and flange 66 is fastened by bolts 67 to the web 58.

The flanges 61 and 66 are provided with 50 retainers 69 which may be annular lips projecting inwardly from said flanges over the tread seat to hold the segments in place. The collar 59 is more than twice the length of the retainer 69; so that when the bolt 55 67 is loosened, the clamp ring may be slipped away from the web far enough to allow tread segments to be withdrawn and inserted for replacement in case of wear. The flange 61 is provided with sprocket teeth 60 to receive the sprocket chain 45 or 46 as the case may be.

The mid-planes of the grooves 71 are normal to the axis of the drum and each groove is of sufficient width to accommodate 65 the buckets 13 on the line and are provided

with center recesses 72 to accommodate the line 14. The stops 15 and 16 are of less diameter than the buckets, so that when a stop contacts with one of the treads it lifts the line from the recess and minimizes the jar of the bucket passing the drum.

The block 73 of the take-up pulley 34 is provided on one side with upwardly and downwardly extended arms 74 having guides 75 that run along the supporting line 17 to center the descending limb of the line 14 relative to the descending tubing 9; and the line 14 is led from the bottom of the drum over said take-up pulley 34, down through the descending tubing 9 and around the foot-wheel and up through the ascending tubing 5 5" and over the upper drum 36; and thence around the drums a sufficient number of times to give the required driving friction.

The foot-wheel is provided internally with a ball raceway *c* for the antifriction balls 8; and the stub axles 7 are supported in seats 77 in the foot 1 and are beveled at their ends to jointly form a raceway 78 90 aligned with the raceway *c* to receive the antifriction balls 8.

Antifriction lateral balls 79 are mounted in seats 80 in the foot 1, said seats being of sufficient diameter at their outer ends to receive the balls 79 and retaining plugs 81 screwed thereinto and hollowed out at their inner ends to accommodate the balls, serve to hold the balls in place to support the foot-wheel against lateral displacement.

To assemble the foot the stub axles 7 are inserted in their seats 77 while the opposite halves of the foot are separated. The balls 79 being in place, one-half of the foot will be brought into horizontal position with the inner side uppermost. One of the stub axles 77 will then be inserted into the seat therefor and the foot-wheel will be placed thereon and the antifriction balls 8 be put into the race-way formed by the foot wheel and the bevel of the stub axle. Then the other stub axle, being placed in the seat in the other foot-piece, will be brought with said other foot-piece into position shown in Fig. 6, so that the foot-wheel is carried by balls in the race-way formed between two stub axles. After the parts have been brought together they are secured by the bolts 2.

In practical operation when there is in the well sand of such compactness that the weight of the pump will not be sufficient to force the digger to sink into the sand, the bull wheel will be operated to raise and lower the pump stock the same as a reciprocating drill, thereby breaking and stirring up the sand and making it loose enough so that the pump can settle down through it. Then when the pumping line is driven the sand will be carried out with the oil and water.

As the pump is lowered slotted couplings *p* and slotted tubing sections *q* are applied to the upper core section the top section of the ascending tubing being raised to allow 5 a slotted tubing section to be applied beneath it. The slots *r* and *s* of the slotted couplings and sections allowing the same to be brought onto the pumping line after which they are temporarily clamped into 10 place on the core section which closes the slots, thus forming top extensions of the tubing to allow the pump stock to be lowered until all the slack is taken up whereupon the pump stock may be raised, the 15 slotted tubing sections be removed, the pump line be cut, additional unslotted tubing sections placed on the line, a new section of pumping line spliced into the old to give the new slack thereby and the pump 20 stock then lowered into the well; whereupon the operation of elevating the oil, water and sand may be proceeded with as before.

We claim:

1. In an oil and water elevator, the combination with a foot, having a foot-way therein; of a foot-wheel in the foot; descending tubing leading down to the foot-way; ascending tubing leading up from the foot-way and provided with an inlet above 25 said foot-way; a driving shaft; driving sprocket wheels on the driving shaft; reverse ratchet clutches to connect the driving shaft with the driving sprocket wheels respectively; drums on opposite sides of the 30 driving shaft; sprocket wheels for the drums respectively; a sprocket chain connecting one of the driving sprocket wheels with one of the sprocket wheels of one of the drums; a sprocket chain connecting the other driving 35 sprocket wheel with the sprocket wheel of the other drum; and an endless pumping line led over the pulley, wound around the drums, led through the descending tubing and around the foot-wheel in the foot-way 40 and through the ascending tubing.
2. In an oil and water elevator, the combination with a foot having a foot-way therein; of a foot-wheel in the foot; descending tubing leading down to the foot-way; ascending tubing leading up from the foot-way and provided with an inlet above 45 said foot-way; a driving shaft; driving sprocket wheels on the driving shaft; reverse ratchet clutches to connect the driving shaft with the driving sprocket wheels respectively; drums on opposite sides of the 50 driving shaft; sprocket wheels for the drums respectively; a sprocket chain connecting one of the driving sprocket wheels with the sprocket wheel of one of the drums; a sprocket chain connecting the other driving 55 sprocket wheel with the sprocket wheel of the other drum; an endless pumping line led over the pulley, wound around the drums, led through the descending tubing and around the foot-wheel in the foot-way 60 and through the ascending tubing.
3. In an oil and water elevator, the combination with a foot having a foot-way therein; of a foot-wheel in the foot; descending tubing leading down to the foot-way; ascending tubing leading up from the foot-way and provided with an inlet above 65 said foot-way; a driving shaft; driving sprocket wheels on the driving shaft; reverse ratchet clutches to connect the driving shaft with the driving sprocket wheels respectively; drums on opposite sides of the driving shaft; sprocket wheels for the drums respectively; a sprocket chain connecting one of the driving sprocket wheels with the sprocket wheel of one of the drums; a sprocket chain connecting the other driving sprocket wheel with the sprocket wheel of the other drum; an endless pumping line led over the pulley, wound around the drums, led through the descending tubing and around the foot-wheel in the foot-way and through the ascending tubing; and means to raise and lower said pulley.

3. In an oil and water elevator, the combination with a foot having a foot-way therein; of a foot-wheel in the foot; descending tubing leading down to the foot-way; ascending tubing leading up from the foot-way and provided with an inlet above said foot-way; a driving shaft; driving sprocket 70 wheels on the driving shaft; reverse ratchet clutches to connect the driving shaft with the driving sprocket wheels respectively; drums on opposite sides of the driving shaft; sprocket wheels for the drums respectively; a sprocket chain connecting one of the driving sprocket wheels with the sprocket wheel of one of the drums; a sprocket chain connecting the other driving sprocket wheel with the sprocket wheel of the other drum; an endless pumping line led over the pulley, wound around the drum, led through the descending tubing and around the foot-wheel in the foot-way, and through the ascending tubing; means to raise and lower said pulley.

3. In an oil and water elevator, the combination with a foot having a foot-way therein; of a foot-wheel in the foot; descending tubing leading down to the foot-way; ascending tubing leading up from the foot-way and provided with an inlet above said foot-way; a driving shaft; driving sprocket 75 wheels on the driving shaft; reverse ratchet clutches to connect the driving shaft with the driving sprocket wheels respectively; drums on opposite sides of the driving shaft; sprocket wheels for the drums respectively; a sprocket chain connecting one of the driving sprocket wheels with the sprocket wheel of one of the drums; a sprocket chain connecting the other driving sprocket wheel with the sprocket wheel of the other drum; an endless pumping line led over the pulley, wound around the drum, led through the descending tubing and around the foot-wheel in the foot-way, and through the ascending tubing; means to raise and lower said pulley.

4. In an oil and water elevator, the combination with a foot having a foot-way therein; of a foot-wheel in the foot; descending tubing leading down to the foot-way; ascending tubing leading up from the foot-way and provided with an inlet; two drums; a pulley; an endless pumping line wound around the drums led over the pulley and through the descending tubing, through the foot-way around the foot-wheel and through the ascending tubing; and means to drive one of the drums.

5. In an oil and water elevator, the combination with a foot having a foot-way therein; of a foot-wheel in the foot; descending tubing leading down to the foot-way; ascending tubing leading up from the foot-way and provided with an inlet; two drums; a pulley; an endless pumping line wound around the drums led over the pulley and through the descending tubing, through the foot-way around the foot-wheel and through the ascending tubing, and means to drive the drums simultaneously.

6. In an oil and water elevator, the combination with a foot having a foot-way therein; of a foot-wheel in the foot; descending tubing leading down to the foot-way; ascending tubing leading up from the foot-way and provided with an inlet; two drums; a pulley; an endless pumping line wound around the drums led over pulley and through the descending tubing, through the foot-way and around the foot-wheel and through the ascending tubing, and compensating means to drive the drums.

7. In an endless line oil and water elevator, the combination with a pumping line;

of two drums around which said pumping line is wound; a driving shaft between the drums; sprocket wheels journaled on the driving shaft; ratchet clutches fixed on the driving shaft to drive the sprocket wheels in one direction; sprocket wheels fixed to the drums; sprocket chains connecting one of the driving sprocket wheels with the sprocket wheel of one of the drums; a sprocket chain connecting the other sprocket wheel with the sprocket wheel of the other drum; a foot wheel around which the pumping line is led; a foot in which the foot wheel is journaled; said foot being provided with a foot-way; a take-up pulley over which the pumping line is led; means to raise and lower the take-up pulley; a core connected with the foot; and pumping tubing provided with an inlet connected with the core, and communicating with the foot-way; said pumping line being led through the pumping tubing.

8. An endless line oil and water elevator, comprising an endless line, buckets thereon, tubing having its intake located above the lower bend of the line a distance that is greater than that between the buckets, and means to drive the line.

9. An endless line oil and water elevator, comprising an endless line, buckets thereon, tubing having its intake located above the lower bend of the line so that the material entering the inlet may be caught by the ascending buckets and thereby prevented from reaching said lower bend, and means to drive the line.

10. In an endless line oil and water elevator the combination with a pumping line; of two drums around which said pumping line is wound; a driving shaft between the drums; sprocket wheels journaled on the driving shaft; ratchet clutches fixed on the driving shaft to drive the sprocket wheels in one direction; sprocket wheels fixed to the drums; sprocket chains between one of the driving sprocket wheels and the sprocket wheel of one of the drums; a sprocket chain between the other driving sprocket wheel and the sprocket wheel of the other drum; a foot-wheel around which the pumping line is led; and a take-up pulley over which the pumping line is led.

11. An oil and water elevator comprising a foot provided with a bucket-way; a foot wheel in the foot; descending tubing leading down to the bucket-way; ascending tubing leading up from the bucket-way, and provided above the bucket-way with an inlet and an outlet; a line provided with buckets to fit the ascending tubing; and means to drive the line.

12. An oil and water elevator comprising a foot provided with a bucket-way; a foot wheel in the foot; descending tubing leading down to the bucket-way; ascending

tubing leading up from the bucket-way, and provided above the bucket-way with an inlet and an outlet; the bore of the descending tubing being of considerably greater diameter than the buckets and the bore of the ascending tubing practically fitting the buckets; a line provided with buckets to fit the ascending tubing; and means to drive the line.

13. In an oil and water elevator, the combination with a foot wheel; a take-up wheel and an endless line provided with buckets; of drums around which the line is wound, said drums having grooves to accommodate the buckets and channels in the grooves to accommodate the line.

14. In an oil and water elevator the combination with a core provided with grooves on opposite sides, of tubing equal in length to the core seated in the grooves respectively and projecting from one end of the core; said core projecting from the other end of the tubing and clamps to fasten the tubing to the core.

15. In an oil and water elevator the combination with a core section provided with grooves on opposite sides, of another core section provided with grooves on its opposite sides, and staggered pairs of tubing sections, fastened to opposite sides and of equal length with said core sections.

16. The combination with two pairs of tubing sections, of core sections, clamps fastening the tubing sections and core sections together, the tubing sections of each pair being symmetrically disposed with relation to each other and projecting at one end beyond the end of a core section, and a slip coupling connecting the ends of the tubing sections of one pair with the ends of the tubing sections of another pair.

17. In an endless line oil and water elevator, a pump stock section comprising a core section, two tubing sections of equal length with the core section and in staggered relation thereto, and means to clamp the tubing sections and core sections together.

18. In an endless line oil and water elevator, a pump stock comprising pump stock sections respectively composed of a core section and tubing sections, and means fastening the core sections and tubing sections together, the core sections being in staggered relation with the tubing sections; couplings connecting the tubing sections together, and means to clamp the tubing sections and core sections together.

19. In an endless oil and water elevator, a pump stock comprising pump stock sections respectively composed of a core section and tubing sections, and means fastening the core section and tubing sections together, the core sections being in staggered relation to the tubing sections; cou-

plings connecting the tubing sections of the pump stock sections together; means to clamp the tubing sections and core sections together; a cable fastened to the lower core section, and means connecting the core sections with the cable.

20. In an endless line pump, a pump stock comprising pump stock sections respectively composed of a core section and 10 tubing sections, and means fastening the core sections and tubing sections together, the core sections being in staggered relation with the tubing sections; couplings connecting the tubing sections of one core section 15 with those of another core section; means to clamp the tubing sections and core sections together at the pump stock joints, a cable fastened to the lower core section; and hook-bolts clamping the core sections, 20 respectively, to the cable.

21. In an endless line oil and water elevator, the combination with a foot provided with a foot-way and chamber; a foot-wheel in the chamber; descending and ascending 25 tubing connected with the foot and communicating with the foot-way; a metal core section provided with a bore between the ascending and descending tubing and above the foot; a cable extending in the bore and 30 having its strands spread apart therein; metal molded in the core section to hold the strands; core sections above the core; clamps fastening the tubing to the core sections, and means to clamp the cable to the core sections 35 respectively.

22. In an oil and water elevator, the combination with a foot-wheel carrying foot and a lower core section, of means fastening the lower core section to the foot; upper 40 core sections above said lower core section; a cable fastened to the lower core section, and means securing the upper core sections to the cable.

23. An oil and water elevator comprising 45 descending and ascending tubing; a foot provided with a foot-way at the bottom of the tubing; a foot-wheel in the foot; a pumping line led around the foot-wheel in the foot-way and provided with buckets; 50 and means to drive the line; there being an inlet to said foot-way, the inlet being located in the ascending tubing of the pump at a distance above the foot-wheel.

24. An oil and water elevator comprising 55 descending and ascending tubing; a foot fastened to the tubing and provided with a foot-way communicating with the descending and ascending tubing; a foot-wheel in the foot-way; a line provided with 60 buckets and running in the foot-way; there being an inlet to the foot-way above the foot-wheel; a digger on the lower end of the foot-way, and means to raise and lower the foot-way, digger and tubing.

65 25. An oil and water elevator pump stock

comprising core sections; descending tubing; ascending tubing; slotted tubing sections having their slots closed by the core sections; means to fasten the core sections together, and means to fasten the tubing 70 sections to the core sections.

26. The combination with a foot provided with a foot-way, of descending and ascending tubing communicating with the foot-way; core sections between the tubing; a 75 cable; means connecting the cable with the core sections; an endless line in the tubing and foot-way; tubing sections provided in their sides with slots to allow passage therethrough of the line; and means to clamp the 80 slotted tubing sections against the core sections, the slots being closed by the core sections.

27. In an oil and water elevator, a pump stock comprising a foot provided with a 85 chamber and a foot-way; descending and ascending tubing communicating with the foot-way; a core above the foot and between the tubing; means fastening the core and tubing together; an endless line in the tubing and foot-way; and means to drive the line; there being an inlet into the tubing.

28. In an endless line oil and water elevator, the combination with a foot provided with a chamber and a foot-way; of descending 90 tubing connected with the foot and of the same diameter as the foot-way; ascending tubing of less diameter than the foot-way and provided with an inlet above the foot-way; a wheel in the chamber; and an endless line led around the wheel and provided with buckets fitting the ascending tubing.

29. In an oil and water elevator, the combination with a foot having a foot-way 105 therein; of descending and ascending pump tubing connected with the foot-way; a core connected with the foot; clamps clamping the tubing to the core; a line fastened to the core, and means for raising and lowering 110 the line.

30. In an oil and water elevator, the combination with a pump stock comprising descending and ascending tubing, a foot at the bottom of the tubing; a foot wheel in 115 the foot; an endless pumping line led around the foot-wheel; means to drive the line; of a supporting line to support the pump stock and foot; means to operate the supporting line to raise and lower the foot; a take-up pulley over which the line is led, and means to raise and lower the take-up pulley.

31. In an endless line oil and water elevator, the combination with a pump stock 125 comprising descending and ascending tubing and a foot having a foot-way communicating with said tubing and provided with a foot-wheel; of a supporting line to support the pump stock and foot; a pumping 130

line led through the tubing and foot and around the foot-wheel; driving mechanism for the pumping line; a take-up pulley for the pumping line; means to operate the 5 take-up pulley; and a guide connected with the take-up pulley and running on the supporting line.

32. In an endless line oil and water elevator, the combination with a pump stock 10 comprising descending and ascending tubing and a foot having a foot-way communicating with said tubing and provided with a foot-wheel; of a supporting line to support the pump stock and foot; a pumping 15 line led through the tubing and foot and around the foot-wheel; driving mechanism for the pumping line; a take-up pulley for the pumping line; and means to operate the take-up pulley.

20 33. In an endless line oil and water elevator, the combination with a pump stock comprising descending and ascending tubing and a foot having a foot-way communicating with said tubing and provided with 25 a foot-wheel; of a supporting line to sup-

port the pump stock and foot; a pumping line led through the tubing and foot; driving mechanism for the pumping line; a take-up pulley for the pumping line; a 30 guide comprising two arms connected with the take-up pulley and running on the supporting line, and means to support the take-up pulley.

34. An endless line oil and water elevator comprising a fluid excluding foot, tubing 35 extending up from said foot and provided with an intake, an endless line running through said foot and tubing, and buckets on said line, the distance between adjacent buckets being less than the distance between 40 the lower end of the tubing and the inlet.

In testimony whereof, we have hereunto set our hands at Los Angeles, California, this 17th day of November, 1911.

THOMAS HARVEY McDONALD.
STEPHEN W. MACK.

In presence of—
JAMES R. TOWNSEND,
L. BELLE RICE.
